UNITED STATES PATENT OFFICE.

LOUIS FRIDEZ, OF BUFFALO, NEW YORK.

MECHANICAL STOKER.

No. 850,919.

Specification of Letters Patent.

Patented April 23, 1907.

Application filed July 23, 1906. Serial No. 327,317.

To all whom it may concern:

Be it known that I, LOUIS FRIDEZ, a citizen of the United States, residing at Buffalo, in the county of Erie and State of New York, have invented a new and useful Improvement in Mechanical Stokers, of which the following is a specification.

This invention relates more particularly to the class of furnace-stokers comprising rows or series of rake-fingers adapted to enter between the grate-bars and means for moving the fingers back and forth and up and down, so as to loosen the fuel and sift the ashes through the grate.

One of the objects of my invention is to provide a simple stoking device of this character which effectually acts upon all portions of the fuel.

A further object of the invention is to so construct the stoking device that the same can be adjusted to feed the fuel backward more slowly on the rear part of the grate than on its front part when the fuel burns slowly, owing to the checking of the draft.

In the accompanying drawings, consisting of two sheets, Figure 1 is a fragmentary longitudinal section of a steam-boiler furnace provided with the improved stoker, showing the raking-frame elevated to the same level at both ends of the grate. Fig. 2 is a horizontal section in line 2 2, Fig. 1. Fig. 3 is a transverse section in line 3 3, Fig. 1. Fig. 4 is a section similar to Fig. 1, showing the rear end of the raking-frame lowered. Fig. 5 is a fragmentary longitudinal section in line 5 5, Fig. 2. Fig. 6 is a transverse section in line 6 6, Fig. 5.

Similar letters of reference indicate corresponding parts throughout the several views.

A indicates the bars of the grate, which may be of any ordinary construction.

The stoking device consists of a raking-frame comprising longitudinal rake-bars B, arranged below the grate and carrying rake fingers or teeth b, which extend upwardly therefrom and pass freely between the grate-bars. The longitudinal rows or series of rake-fingers extend nearly from end to end of the grate, and each rake-bar B may carry one or more rows of fingers. In the construction shown three rows are secured to each rake-bar, as seen in Fig. 3.

The rake-bars are carried at or near opposite ends by the cranked portions of a pair of transverse crank-shafts C C', which extend across the ash-pit, and are journaled in the

side walls of the furnace. As shown in Figs. 1, 3, and 4, the rake-bars are provided with suitable bearings d, which embrace the cranks of said shafts. These shafts extend through one side of the furnace and are suitably geared together to turn in unison. In the preferred construction shown they are connected by a sprocket-chain e, passing around sprocket-wheels e' e'', secured to their projecting ends, and they are turned by a hand-crank f, secured to a longitudinal shaft f', which is connected with the front crank-shaft by bevel-gears f''. This hand-crank is arranged at the front of the furnace, where it can be conveniently operated by the attendant.

The cranks of the shafts C C' are arranged in corresponding positions and are of the same length, so that upon rotating the shafts all the rake-fingers move backward and forward and up and down to the same extent, the rear fingers of the raking-frame as well as the front ones moving in circular paths.

In the operation of the device the continuous rotation of the crank-shafts C C' in the direction of the arrow causes the rake-fingers to be moved upwardly and rearwardly during a half-turn of the cranks and downwardly and forwardly during the other half-turn thereof. The throw of the cranks is such or the fingers are of such a length that the latter project above the surface of the grate during their rearward stroke and recede below said surface during their forward stroke, so as to loosen and stoke the fire and at the same time gradually push the fuel toward the rear end of the grate. By causing the transverse rear rows of fingers as well as the front rows to act upon the fuel only during their rearward stroke when they are projected the fingers do not displace the fuel both forward and backward, but only backward, thus avoiding the formation of a gap or opening in the fuel upon the rear end of the grate, which occurs by the use of devices in which the rake-fingers move the fuel back and forth. When such gaps are formed, the rear end of the grate is uncovered, allowing cold air to ascend through the same and cooling off the furnace and impairing the draft. By the improved construction herein shown and described the rear as well as the front rake-fingers of the stoker are below and out of reach of the fuel during their receding stroke, thus pushing or displacing the fuel only in a rearward direction, keeping the grate covered and prevent-

ing the formation of such cold-air gaps or passages.

When the draft is checked, the fuel burns slower on the rear portion than on the front portion of the grate, and it is therefore desirable to feed or push the fuel backward more slowly or to a less extent on the rear part of the grate under these conditions. This is accomplished by lowering the rear portion of the raking-frame relatively to its front portion, as shown in Fig. 4, so that the fingers project into the adjacent portion of the fuel-bed to a less extent than the front fingers, and hence have a reduced displacing or feeding action on the fuel. In the preferred construction shown in the drawings rear crank-shaft C' is for this purpose arranged in vertical slots or vertically-elongated bearings c, as illustrated in Fig. 6, and is supported at its ends upon rotary cams or eccentrics g, secured to opposite ends of a transverse rock-shaft G, journaled in the side walls of the furnace below the rear crank-shaft. One of these eccentrics is provided with an arm g', to which is connected an operating-rod H, which terminates at the front of the furnace. Upon turning this rock-shaft by means of the rod H so that the wide portions of the cams are presented to the shaft the latter and the rear ends of the rake-bars are raised to their normal position, in which all of the rake-fingers project above the surface of the grate to the same extent, as shown in Fig. 1, while upon turning the shaft in the opposite direction the narrow portions of the cams are presented thereto and the rear portion of the raking-frame is permitted to descend, as shown in Fig. 4.

The operating-rod H may be locked in position by any suitable means. The preferred device consists of a bracket H' for the rod, secured to the front wall of the furnace and provided with a clamping-screw h or other suitable means, by which the rod may be secured in either of its positions.

A dumping grate-section I may be arranged at the rear end of the main grate, if desired, this section forming no part of my invention and being operated by any suitable means.

50 I claim as my invention—

1. The combination of a grate, front and rear crank-shafts arranged below the same and both capable of complete rotary movement, actuating mechanism for said shafts, and a raking-frame carrying rake-fingers which enter between the grate-bars and having its end portions journaled upon the cranks of said front and rear shafts, whereby all the fingers of said frame move to and fro and up and down in circular paths and dis-

place the fuel only in a rearward direction, substantially as set forth.

2. The combination of a grate, front and rear crank-shafts arranged below the grate and both capable of complete rotary movement, gearing connecting said shafts to cause the same to rotate in unison, and rake-bars arranged lengthwise of the grate-bars and carrying rake-fingers which enter between the grate-bars, said rake-bars being journaled at opposite ends upon the cranks of said shafts, whereby both ends of the bars and all the rake-fingers move back and forth and up and down in circular paths, substantially as set forth. 71

3. The combination of a grate, a raking-frame movable lengthwise of the grate-bars and carrying fingers which enter between the same, and means for adjusting one end of the raking-frame vertically relatively to its other end, substantially as set forth. 80

4. The combination of a grate, a raking-frame movable lengthwise of the grate-bars and carrying fingers which enter between the same, front and rear shafts arranged below the grate and having cranks upon which the front and rear portions of the raking-frame are journaled, the rear shaft being capable of vertical adjustment, and means for adjusting the last-named shaft, substantially as set forth. 85

5. The combination of a grate, a raking-frame movable lengthwise of the grate-bars and carrying fingers which enter between the same, front and rear shafts arranged below the grate and having cranks upon which the front and rear portions of the raking-frame are journaled, the rear shaft being capable of vertical movement, and cams for adjusting the last-named shaft, substantially as set forth. 95

6. The combination of a grate, a raking-frame carrying fingers which enter between the grate-bars, front and rear shafts arranged transversely below the grate and having cranks upon which the front and rear portions of the raking-frame are journaled, said rear shaft being capable of vertical adjustment, a transverse rock-shaft arranged below said adjustable shaft and carrying cams which act upon the latter shaft, and means for turning said rock-shaft, substantially as set forth. 105

Witness my hand this 14th day of July, 1906.

LOUIS FRIDEZ.
